Electric Company, a corporation of New York

Application April 23, 1946, Serial No. 664,165
In Great Britain August 9, 1943

Section 1, Public Law 690, August 8, 1946
Patent expires August 9, 1963

4 Claims. (Cl. 176—122)

1

Our invention relates to electric discharge devices, and more particularly to electric discharge lamps of the high-pressure type such as high-pressure mercury vapor electric discharge lamps.

It is well known that one of the main difficulties in constructing high-pressure mercury vapor lamps is to prevent the anode, which is constructed usually of a refractory metal, such as a tungsten, from overheating. That is, one of the principal desirable features is to prevent the anode from becoming so hot that the useful life of the lamp is greatly reduced. Within a certain region of operation, that is within a power consumption having an upper limit of about 10 kilowatts, such overheating can be prevented by increasing the size of the anode; but beyond this limit, this expedient cannot be applied. One reason for this limitation on the ability to increase the power rating is the difficulty in making tungsten blocks sufficiently large. Secondly, it has been found that beyond a certain size further increase thereof is ineffective.

The heat, incident to the operation of an anode, is usually generated at the place where the electric discharge terminates, hereinafter termed the termination surface. In the case of a cylindrical anode this place of heat generation is the middle part of the circular end face of an anode, and the heat is radiated from the marginal path of this end face and from the cylindrical surface of the anode. Increase in the size of the anode causes the radiating surface to be increased, but there is also an increase in the length of the path by which heat is transmitted from the termination surface through the body of the anode to the radiating surface so that, owing to the temperature within the anode, the temperature of the terminating surface is not so effectively reduced. It has also been found, when the anode is cylindrical, that there is no substantial advantage as regards heat dissipation, in making its length exceed its diameter. In accordance with our invention described herein-after we provide structures for high-pressure discharge lamps wherein the above described limitations on heat dissipation may be obviated.

It is an object of our invention to provide new and improved electric discharge devices or lamps.

It is another object of our invention to provide new and improved high-pressure electric discharge lamps employing an ionizable medium, such as a gas or a vapor.

It is a further object of our invention to provide new and improved high-pressure mercury vapor discharge lamps having constructions

2

which permit the dissipation of greater amounts of heat, than that afforded by the prior art arrangements, without entailing an excessive reduction in life of the lamps while operating at high power input.

In accordance with salient aspects of our invention we provide constructions, particularly electrode constructions for electric lamps employing an ionizable medium at high pressure, 10 wherein the electrodes are arranged to permit dissipation of large amounts of heat incident to operating the lamps at high power. We provide electric discharge lamps employing ionizable media at high pressures and which are provided 15 with a plurality of individual anodes positioned so that each arc-supporting surface, or termination surface thereof, has an uninterrupted view of the arc-supporting surface of the single associated cathode. By virtue of such an electrode 20 structure, a plurality of arc discharges are simultaneously established between the anodes and the cathode, and the anode structure is peculiarly suitable for dissipating large amounts of heat. More specifically, in one embodiment we employ 25 a plurality of anodes in a high-pressure mercury vapor lamp, the anodes being associated with a single cathode and the cathode is arranged with its termination surface upon one side of a plane transverse to the discharge path between the 30 cathode and the anodes, or more particularly, transverse to the axis of the group or cluster of discharge paths established between the single cathode and the plurality of anodes which conduct current simultaneously. The anodes are arranged with their termination surfaces in a 35 cluster on the opposite side of the plane and are so disposed that each has an uninterrupted view of the termination surface of the cathode. When the lamp is in operation, the discharge columns terminating on the different anodes cooperate to 40 form a compact light source.

We have found that the anodes may be constructed in the form of cylinders, the ends of which constitute the termination or arc supporting surfaces, and may be positioned symmetrically about the electrode axis and having their axes parallel to one another. These anodes cylinders may be arranged to be out of physical contact with each other, although it is within 45 the scope of our invention to arrange these anodes to be in physical contact, but having poor electrical and thermal contact, with one another over a very small part of their contiguous surfaces. The provision of a plurality of relatively small 50 anodes, instead of employing a single large anode,

overcomes the difficulty of excessive heating in high-power lamps.

The life of a lamp of the type above described, employing a single anode, depends on the watts dissipated per unit volume of the discharge column terminating on the anode. For lamps having cylindrical anodes, in order to secure a life of at least ten hours, which is a reasonable life in certain applications of high power lamps, the maximum permissible dissipation may be expressed as:

$$W = D/1.8$$

where W denotes the watts per cu. mm. of the discharge column and D represents the diameter of the anode in mm. The above expressed relation prevails where the anode is of tungsten and its length is such that an increase in length will not appreciably reduce the temperature of its termination surface, where the diameter of the discharge column is measured by the points having a brightness equal to one-half of the maximum brightness on the axis of the discharge column, and lastly where the axis of the discharge column is substantially coincident with the axis of the cylindrical anode.

In employing lamps constructed in accordance with our invention, it is desirable to consider the possible obstruction of the light from one discharge column by an anode in which it does not terminate. Where a concentrating reflector, such as a parabolic mirror, is employed with lamps having the above described features, one suitable arrangement is to position the cathode so that its termination surface lies on the axis of the reflector and is nearer to it than any of the termination surfaces of the anodes, the termination surfaces of the latter being symmetrically distributed around the axis. Alternatively, in order to reduce obscuration, the termination surface of the cathode may be placed off the axis and be nearer to the reflector than the termination surfaces of any of the anodes. In which instance, the termination surface of the cathode may then be nearer to some anodes than others. By the adjustment or selection of appropriate values of stabilizing resistors in series with the different anodes, the power can be distributed among the anodes so that the dissipation per cu. mm. of the discharge column is the same for all columns.

For a better understanding of our invention reference may be had to the following description taken in connection with the accompanying drawing and its scope will be pointed out in the appended claims. Fig. 1 diagrammatically illustrates an embodiment of our invention as applied to a multiple anode, single cathode high-pressure mercury vapor lamp wherein a reflector is positioned so that its axis is substantially coincident with the axis of the discharge established between the electrodes. Fig. 2 diagrammatically illustrates a modification of the embodiment of the invention shown in Fig. 1 wherein the cathode seal structure is positioned at the side or bottom of the envelope so that it does not obscure the light path from the arc discharge to the reflector. Fig. 3 is a transverse view showing one possible arrangement of the multiple-anode structure and includes a heat reflector such as a tungsten disc which is symmetrically placed within the cluster of anodes.

Referring now more particularly to Fig. 1, our invention is there illustrated as applied to an electric discharge device, such as a high-pressure

mercury vapor lamp, comprising an enclosing envelope 1 provided with suitable seal structures, described hereinafter. We provide, within the envelope, an ionizable medium such as mercury vapor, a single cathode 2 preferably constructed in cylindrical form as illustrated and having a tapered end providing an arc-supporting or termination surface 3 which supports the arc discharge, or more specifically the plurality of arc discharge columns established between the cathode 2 and a plurality of anodes 4-11 inclusive. The anodes 4-11 inclusive may be arranged in a cluster symmetrically placed about the axis of the electrodes or the axis of the discharge path of the lamp, as shown in detail in Fig. 3.

The envelope 1 may be constructed of quartz and may have an external diameter of approximately 150 mm. with walls about 3.5 mm. thick. The cathode 2 is preferably constructed of a tungsten block substantially 25 mm. long and 12 mm. in diameter. Of course, any suitable starting arrangement or starting electrode of the conventional type (not illustrated) may be employed for initiating the establishment of the arc discharge between the main or principal electrodes comprising the cathode 2 and the plurality of anodes. The cathode 2 may be supported by a suitable inner lead-in conductor 12 such as a tungsten rod, having a diameter of 6 mm., and is connected to an exterior energizing circuit such as a direct current circuit (not shown) through an outer lead 13 constituting a terminal for the lamp. Conductor or rod 12 is of course embedded in a suitable sealing structure such as a vitreous seal 14 which in turn is positioned within a suitable neck or tubing 15 constituting a part of the envelope 1.

In like manner the anodes 4-11, inclusive, may be constructed of tungsten cylinders. We have found that in one modification of our invention the anodes may be constructed of tungsten cylinders having a diameter of 8 mm. and being about 20 mm. long, each supported on 2 mm. tungsten rods 16. The tungsten rods 16 are connected to an exterior energizing circuit through a multiple strip seal 17 which supports eight individual strips 18, all of which are embedded within the seal and the latter being sealed to the neck or tube 19 constituting a part of the enclosing envelope 1. External lead conductors are connected to the strips 18 and may comprise the anode terminals. For the dimensions above set forth, we have found that each strip 18, and its associated anode, may conduct 20 amperes without sacrificing the desired lamp life.

As shown in Fig. 3 the anodes are arranged so that their axes are parallel to one another and parallel to the principal axis of the main electrodes of the lamp. Furthermore, the anodes 4-11 are positioned so that their termination surfaces lie in a plane transverse to the axis of the main electrodes and are symmetrically arranged around this axis in a ring-shaped cluster. In this form of our invention all of the anodes are equidistant from the cathode 2, and each has an uninterrupted view of the termination surface 3 of the cathode 2.

Where it is desired to employ a concentrating reflector, such as a parabolic mirror 20, the latter may be positioned so that its axis is substantially coincident with the axis of the main electrodes of the lamp and so that the center of the light intensity produced by the arc discharge coincides with the focus of the mirror. One suitable arrangement is that illustrated in Fig. 1 where the

termination surface 3 of the cathode lies on the axis of the mirror 20, and is nearer to it than any other termination surfaces of the anodes; the latter termination surfaces being symmetrically distributed around the axis.

In view of the above given dimensions and in accordance with the general principles of our invention described herein it will be appreciated that the distance between the terminations of the discharge, that is the distances between the terminating surface of cathode 2 and the terminating surfaces of the plurality of anodes which is 20 mm., is less than the distances of the termination surfaces from the inside of the envelope 1.

The embodiment of our invention shown in Fig. 1 is peculiarly adaptable for operation on direct current wherein the plurality of exterior lead-in conductors 21 may be connected to a direct current circuit (not shown) through a plurality of stabilizing resistances, not shown in Fig. 1 but illustrated generally in Fig. 2. These stabilizing resistances may be located inside the envelope, in which case it may be desirable to connect a still further series resistance which is common to all the individual resistances and positioned exterior to the envelope. The degree to which the amounts of power dissipated in the individual anodes can be adjusted relative to each other is thereby greatly reduced as contrasted with the situation where the individual stabilizing resistances are positioned exterior to the envelope affording individual adjustment thereof. The arrangement illustrated in Fig. 1 contemplates the use of external stabilizing resistances. If it is desired to employ resistances having any substantial part within the envelope, these resistances may be suitably constructed of a wire such as tungsten or molybdenum wound on a refractory insulating core such as zirconia, and the wire and the core may act as a support for the anode with which these elements are associated.

In operation, a source of unidirectional potential is applied to the terminals of the lamp and upon initiation of an arc discharge, by auxiliary starting means, the anodes 4-11 inclusive conduct current simultaneously establishing arc discharge columns between their terminating surfaces and terminating surface 3 of cathode 2 thereby establishing, by virtue of their combined effect, a high power light source of great intensity.

A decided advantage of mercury vapor lamps of the high pressure type constructed in accordance with our invention is evidenced by considering the fact that if the discharge column dissipating 25 kilowatts, having a length of 20 mm. and a voltage drop of 156 volts were terminated in a single anode, the discharge would take the form of a cylinder about 11 mm. in diameter, measured between points of one-half maximum brightness which would be about 100,000 candles per square centimeter. The volume of such a discharge column would thus be about 200 cu. mm. and the energy dissipation would be 12.5 watts per cu. mm. of discharge. The minimum diameter of a cylindrical anode, as constructed in accordance with the above described relationship, for a life of ten hours, would therefore be 1.8 times 12.5 or 22 mm. Such an anode would be larger than we have been able to obtain.

Fig. 2 diagrammatically illustrates a further embodiment of our invention as applied to a high-pressure mercury vapor lamp which is similar to the arrangement shown in Fig. 1 and corresponding elements have been assigned like reference

numerals. In the arrangement of Fig. 2 the cathode seal 22, through which the cathode lead 12 passes is positioned at the side of the envelope so that the seal structure does not obscure and does not lie in the path of the reflector or mirror axis. In this arrangement the cathode seal 22 and the cooperating neck or tube of the envelope 1 extend from a side of the envelope and lie in a plane substantially perpendicular to the axis of the principal electrodes and perpendicular to the axis of the reflector. This arrangement offers a further advantage in that the condensed mercury within the envelope 1 will tend to collect there when the lamp is not in operation, and the heat developed at the cathode will accelerate the evaporation of the mercury upon subsequent operation. Individual stabilizing resistances 23, only two of which have been illustrated, may be connected to the outer lead conductors 21 intermediate these leads and the source of direct current (not shown).

Where the anodes 4-11 are arranged in a ring about the axis of the reflector or the axis of the main electrodes, it may be desirable to use a reflecting disc 24, (shown in Fig. 3) and, preferably constructed of tungsten, with its center on the axis of the main electrodes and its plane perpendicular to the axis and within or a short distance behind the ring of termination surfaces 30 of the anodes, in order to prevent loss of power by radiation of the discharge itself through this ring. The use of the disc 24 is optional and when it is desired to employ such a disc we have found that it is preferable to position it about half way along the length of the anodes 4-11.

In another suitable arrangement of the lamp and a reflector, the anodes are so disposed that their termination surfaces lie in or substantially in a common plane and are distributed around a line which is perpendicular to the axis of the reflector and which passes through the termination surface of the cathode. In this case the distance between the termination surface of the cathode and the termination surface of one of the anodes that is nearer to the reflector may be longer than the distance between the termination surface of the cathode and the termination surface of one of the anodes that is farther from the reflector, in order that light from the discharge to the said farther anode may reach the reflector more easily through the gap between the cathode and the said nearer anode.

If the anodes are thus distributed around a line lying in a plane which is perpendicular to the axis of the reflector, the seal through which the anode lead or leads pass and the seal through which the cathode lead passes may both lie along the said line. But there may be an advantage in arranging for the cathode lead to issue from the envelope in a direction approximately perpendicular to the said line; for in this arrangement the anodes are likely to be supported on a lead or leads sealed into the bottom of the envelope, and, if the cathode seal were at the top, it would be heated by convection currents.

What we claim as new and desire to secure by Letters Patent of the United States is:

1. In combination, a high-pressure direct-current mercury vapor electric discharge lamp designed for a power consumption of at least about 10 kw. and comprising a plurality of simultaneously conducting anodes associated with a single cathode, the cathode being arranged with its termination surface upon one side of a plane transverse to the axis of the discharge paths be-

tween the cathode and the anodes, and the anodes being arranged with their termination surfaces in a confined cluster on the opposite side of said plane and so arranged that each has an uninterrupted view of the termination surface of the cathode, and a concentrating reflector positioned so that the termination surface of said cathode lies on the axis of the reflector and is nearer to it than any of the termination surfaces of said anodes.

2. In a high-pressure direct-current mercury vapor electric discharge lamp designed for a power consumption of at least about 10 kw., the combination comprising a plurality of anodes associated with a single cathode, the cathode being arranged with its termination surface upon one side of a plane transverse to the discharge path between the cathode and the anodes and the anodes being arranged with their termination surfaces in a cluster on the opposite side of said plane and so disposed that each has an uninterrupted view of the termination surface of the cathode, and an enclosing envelope structure including a multiple seal for lead conductors supporting said anodes and a seal for supporting the lead conductors and said cathode, said last mentioned lead issuing from the envelope in a direction approximately perpendicular to the axis of the electric discharges established between said cathode and said anodes.

3. In combination, a high-pressure direct-current mercury vapor lamp designed for a power consumption of at least about 10 kw., comprising an enclosing envelope, a single cathode having a termination surface for supporting an arc discharge, a plurality of cylindrical anodes associated with said cathode and each having a termination surface constituted by the end face of

the cylinder, said termination surfaces lying in a plane substantially parallel to the termination surface of said cathode and being symmetrically positioned about the discharge axis, and a multiple-strip seal for lead-in conductors supporting said anodes.

4. A high-pressure direct-current electric discharge lamp designed for a power consumption of at least about 10 kw. and comprising an envelope enclosing an atmosphere of an ionizable medium, a single cathode having a termination surface upon one side of a plane transverse to the electric discharge path, a plurality of anodes disposed with their axes parallel to each other and arranged in a confined cluster about the axis of said discharge path on the opposite side of said plane, and a reflecting disc disposed substantially perpendicular to said axis of the discharge path and within the said cluster of anodes.
